UNITED STATES PATENT OFFICE.

WILLIAM A. RIFE, OF WAYNESBOROUGH, VIRGINIA.

HYDRAULIC RAM OR ENGINE.

SPECIFICATION forming part of Letters Patent No. 357,414, dated February 8, 1887.

Application filed August 3, 1886. Serial No. 209,860. (No model.)

To all whom it may concern:

Be it known that I, WILLIAM A. RIFE, of Waynesborough, in the county of Augusta and State of Virginia, have invented certain new and useful Improvements in Hydraulic Rams or Engines; and I do hereby declare the following to be a full, clear, and exact description of the invention, such as will enable others skilled in the art to which it pertains to make and use it, reference being had to the accompanying drawings, which form part of this specification.

My invention relates to an improvement in hydraulic rams or engines; and it consists in, first, a base or water-chamber having a horizontal portion where the water is admitted from the drive-pipe and a raised portion upon which the air-chamber is placed for the purpose of obtaining an increased suction at each reaction of the water, whereby sufficient air is drawn through a tube or petcock provided for this purpose to keep the air-chamber supplied with air; second, in a hydraulic ram or engine, a drive-pipe for conveying the creek or river water, and a pipe leading from the spring for conveying spring-water into the raised portion of the water-chamber, and which pipe is provided with a stop-cock, whereby the supply of spring-water may be shut off and the creek-water forced to the point of delivery alone, or the stop-cock opened and the spring-water be forced to the delivery alone, and thus the ram be made either single or double acting, as may be desired; third, a pivoted U-shaped lever, which is provided with an escape-valve, an adjustable weight, which can be moved back and forth, so as to regulate the flow of water or force necessary to close the valve; fourth, the combination of a U-shaped lever, which is provided with an escape-valve at one end and a counter or reacting weight at the other, with an adjustable weight, which can be moved back and forth upon the lever, for controlling the opening and closing of the valve.

Figure 1 is a perspective of a hydraulic ram or engine embodying my invention in full, and showing the parts constructed and arranged for the purpose of having the creek-water force the spring-water to the point of delivery. Fig. 2 is a vertical section of the ram, taken through the center of Fig. 1, so as to show all of the

parts in position. Fig. 3 is an enlarged vertical section of the lower portion of the ram, showing the ram arranged for single-acting only. Fig. 4 is a similar view to Fig. 3, showing the pipe which conducts the spring-water attached to the ram, whereby the ram is made double-acting, and also showing the escape-valve open and the flow of the two kinds of water as being influenced by gravity. Fig. 5 is a similar view to Fig. 4, showing the escape-valve closed by the upward force of the escaping water and the delivery-valve open, admitting the spring-water and air into the air-chamber, the spring-water being forced into the chamber by the downward movement of the creek or river water through the drive-pipe. Fig. 6 is a similar view to Fig. 5, the arrows showing the effect produced a moment later by the reaction of the creek or river water after expending the force exerted, as shown in Fig. 5. Figs. 7, 8, 9, 10, 11, and 12 are detail views of the delivery-valve and valve-seat.

A represents the drive-pipe leading from a source of supply of creek or river water down a suitable inclination toward the ram or engine in the usual manner and connected to the horizontal part of the water-chamber B. Upon the horizontal part, and formed as a portion of this water-chamber B, is the escape-valve chamber C. Upon the chamber C is rigidly secured by four hooked bolts, A', a top or plate, D, which forms the escape-valve seat and the support for the lever. This support extends a suitable distance beyond one side of the chamber C and sustains the rocking support E. Crosswise upon this rocking support E is bolted centrally the lower part of a U-shaped lever, F. To the lower end of this lever F is rigidly secured the stem of the escape-valve G. The upper and lower arms of the lever are connected together, so that both ends of this U-shaped lever will rise and fall with the escape-valve G.

Upon the upper arm of the lever is placed a sliding weight, H, which may be moved back and forth on the bar over the pivotal point at the rocking support E, and this weight having a pin to pass through its center and corresponding perforations in the lever, it may be

conveniently fastened at any desired place on the lever. When this weight H is placed between the pivotal point and the escape-valve G, it imparts weight to said valve, and a 5 stronger upward current of water is required under the valve to close it. When the weight is moved in the opposite direction and beyond the pivotal point, the weight of the escape-valve G may be so nearly counterbalanced that 10 a very slight upward current will close it, and yet the passage or orifice through which the water escapes remain the same. Where the usual means are employed to regulate the distance, the escape-valve shall fall to open, or by 15 other means of narrowing or reducing the size of the orifice through which the water has to force its escape, in order to control the flow, the driving or forcing power of the water is reduced, and the constant action of the different parts has a tendency to change the flow of the water by wearing or working loose the adjustable parts.

In the plan here shown the escape-valve may be adjusted to open sufficiently to almost allow 25 a free passage for the water to escape; but the movable weight can be adjusted to cut off the flow to suit the action of the ram or engine, to perfectly control the quantity of water for driving the ram or flowing from the supply per 30 minute.

Attached to the free end of the upper arm of the U-shaped lever is a reacting-weight, I, which is carried above the horizontal line of the lever to which it is attached, as shown in 35 Fig. 5, on the upward stroke, and returns with a reacting downward force, as shown in Fig. 6, assisting the escape-valve G to drop more quickly during the movement of the reaction in the drive-pipe, which reaction in some locations is very short, and if the escape-valve 40 does not fall promptly it will be inclined to remain closed, and thus the action of the ram or engine cease. By the influence of this reacting-weight such inclinations are overcome and 45 constant action kept up.

One end of the water-chamber B is inclined upward or elevated, forming a base upon which is secured, by means of four hooked rods, the air-chamber J, as shown, and which chamber incloses the open end of the water-chamber B. Around this open elevated end of the water-chamber B, upon the base, is formed the delivery-valve seat C', as shown in Fig. 7, and upon which plays a vertically-acting delivery- 55 valve, L.

Up through the under side of the elevated end of the water-chamber, directly under the delivery-valve L, is inserted vertically a spring supply-pipe, M, leading from a spring 60 or other source of fresh-water supply, and which pipe is provided with an overflow-pipe, N, and a check-valve, O. The overflow-pipe N may be made of suitable length, and being adjustable to any angle, the upper end, from 65 which the spring-water momentarily escapes, may be raised or lowered to suit any location

or the action of the ram or engine. Up through the under side of the elevated base, directly into the air-chamber J, is inserted vertically the delivery-pipe P, leading to the place where 70 the spring-water is to be forced or delivered.

Through the extreme upper end of the elevated part of the water-chamber B, and above the level of the escape-valve G, is inserted the 75 petcock R, at which elevation a reliable air-supply for the air-chamber may be attained automatically by the reaction of the water in the drive-pipe, which causes a suction through the petcock, by which the supply of air may be conveniently controlled at will.

It will be seen in Fig. 6 that the petcock or air-tube is inserted at this elevated point, above the level of the escape-valve, so that if 80 there is only sufficient reaction to let the escape-valve open there will be sufficient suction produced at this point, and that it will be increased in proportion to the elevation of the water-chamber. If the air tube or cock is inserted down on a line with or in the drive-pipe, where it has been usually placed heretofore, in many locations the reaction is not sufficient to draw air in at this point, and a tube 85 as an air-feeder proves ineffective, and other complicated means have therefore been employed for forcing air into the air-chamber.

In Fig. 4, the escape-valve being open, the flow commences, influenced by gravity, as shown by the arrows. The creek or river water (shown by dark lines) flows down the drive-pipe A and discharges at the escape-valve G, and the spring-water at the same time flows from the spring, through the pipe M, into the water-chamber B, directly under 90 the delivery-valve L, filling the elevated end of the water-chamber B, and, passing down the inclined portion, comes in contact with the creek or river water at the escape-valve G, thus filling the entire elevated end of the water-chamber B with spring-water, as represented by the light shaded lines.

When the upward 95 current of the escaping water becomes sufficient to raise the valve G, the flow is instantly cut off at the escape-valve, as shown in Fig. 5, and the inertial force of the moving column of creek or river water is exerted upon the spring-water in the upper end of the water-chamber B. The check-valve O in the spring supply-pipe closes to prevent the return of the spring-water through the pipe M, and hence it must pass through the delivery-valve L into 100 the air-chamber J and be discharged through the delivery-pipe P. The spring supply-pipe M being provided with the overflow-pipe N, in which the spring-water may momentarily rise or escape when the check-valve O closes 105 thus prevents any stoppage or check in the flow of the spring-water down the pipe M, the spring-water being always ready to enter the upper end of the water-chamber B the moment the creek or river water has expended 110 its force and recedes, as is shown in Fig. 6 by the return of the arrows. The pressure of the

creek or river water at this moment is relieved at the escape-valve G, which opens, and the delivery-valve L being instantly closed by the pressure in the air-chamber, a suction 5 is produced in the elevated end of the water-chamber B. Air is drawn into the upper end of the water-chamber at the petcock R, and the spring-water again resumes its flow into the water-chamber, replacing the amount of 10 spring-water just driven into the air-chamber J and again filling the space down the incline, following the creek or river water as it recedes. The creek or river water recovers from this reaction and the flow is again resumed, as in Fig. 4, through the escape-valve 15 G. Thus the two waters are caused to play in contact with each other within a properly-limited space, in which the spring-water has such control that no part of the creek or river 20 water can reach or pass through the delivery-valve to the house or other point of delivery. Thus the power of the creek or river water is used to force spring-water, and that in as pure a condition as when it left the spring, without 25 using diaphragms, pistons, or other complicated working parts for keeping the two waters separated. As shown in Fig. 4, the spring supply-pipe M is provided with a common 30 stop-cock, S, whereby the spring-water may be conveniently cut off to act either single or double, delivering either water preferred to the house or other point of delivery, the creek or river water being preferable at times for certain purposes to spring-water when the 35 spring-water is of a hard or mineral nature.

In Fig. 3 the ram is shown as single-acting. The opening A², near the air-feeder, is shown as closed by a plug, Z. As here constructed a part of the driving water only will be forced. 40 When it is desired to make the ram double-acting, the plug Z is removed, and the spring supply-pipe is connected at this point. The inner end of the water chamber being raised upward, as shown, the spring supply and delivery pipes can be swung around in any desired direction, so as to lead to any desired point without the use of additional elbows, curves, or bends.

It will be seen that a hydraulic ram or engine constructed upon this plan has great advantage over those made in the usual way, and which have to be specially constructed at a greater expense for double action. In the plan here shown there is no difference in form 50 of the ram for double or single action. In Fig. 1 it will be seen that the air-chamber is formed with a projecting rim at the top, and the base has rods hooked under its edge, and which pass through the rim and are provided 55 with nuts upon their upper ends, by which rods the air-chamber is drawn water-tight upon the base. The nuts being upon the top of the air-chamber, they are less exposed to mud and water, and can be protected from 60 rust, and the air-chamber can be more conveniently removed than when secured in the usual way by keys or bolts at the bottom.

The main part of the delivery-valve L consists of the face and stem, which stem plays vertically through an L-shaped guide, Q, secured 70 to the base by means of a thumb-screw, W. The square plate or washer V, formed with corner guides on its lower side, and which loosely fit the orifice over which the valve is placed, plays vertically with the valve. A 75 common bolt passes through this guiding-washer and a piece of leather or other suitable material, Y, and through the valve-stem, with nut on top, clamping the leather between the washer and face of the valve. This leather 80 can be easily renewed when worn out, the valve being easily removed by means of the thumb-screw, with scarcely any chance to be improperly replaced.

The objects of my invention are to produce 85 a hydraulic ram or engine that may be applied for either single or double action, in which the air-chamber is automatically supplied with a large volume of air, whereby the greatest possible effective force in a moving column of 90 water may be attained and economically applied, which ram embraces but few working parts, and those parts simply constructed and so arranged that the flow of water can be accurately and conveniently controlled and the few 95 wearing parts easily and cheaply renewed, so that a hydraulic ram or engine may be kept in successful operation by persons possessing little or no mechanical intelligence.

Having thus described my invention, I 100 claim—

1. In a hydraulic ram or engine, the base B, having the end upon which the air-chamber is placed raised upward above its main portion, in combination with an air-feeder consisting 105 of a short tube, which is passed through this raised end and which communicates directly with the outer air, so as to admit air by suction under the valve L at each reaction of the water, substantially as shown. 110

2. In a hydraulic ram or engine, the combination of the base and water-chamber B, having horizontal and inclined portions, and a pipe, M, leading from a spring or other source of fresh-water supply, which pipe is provided 115 with the overflow-pipe N, and a check-valve, O, whereby spring or other pure water is conducted into the ram or engine and forced by power of creek or river water, substantially 120 as described.

3. The combination of the base and water-chamber B, the pipe M, provided with the overflow-pipe N, the check-valve O, and a stop-cock, S, whereby the spring-water may be conveniently cut off or turned on, thus 125 causing the ram or engine to act either single or double, substantially as set forth.

4. In a hydraulic ram or engine, the combination of the base and water-chamber B, the support D connected thereto, a U-shaped 130 rocking lever, F, the escape-valve G, and the weight H, which can be adjusted back and forth upon the lever for the purpose of controlling the flow of water, so that more or less

can be used, as desired, substantially as described.

5. The combination of the base and water-chamber B, the support D connected thereto, the rocking lever F, provided with an adjustable weight, the escape-valve G, connected to the end of the lever, and a reacting-weight, I, which is attached to the free end of the lever, for the purpose set forth and described.

In testimony whereof I affix my signature in presence of two witnesses.

WM. A. RIFE.
